CLAIM

The ornamental design for a fishing rod grip, as shown and described.

DESCRIPTION

FIG. 1 is a perspective view of a fishing rod grip showing the new design;

FIG. 2 is a left side view of the fishing rod grip of FIG. 1; FIG. 3 is a right side view of the fishing rod grip shown in FIG. 1;

FIG. 4 is a front view of the fishing rod grip shown in FIG. 1;

FIG. 5 is a rear view of the fishing rod grip shown in FIG. 1;

FIG. 6 is a top view of the fishing rod grip shown in FIG. 1; and,

FIG. 7 is a bottom view of the fishing rod grip shown in FIG. 1.

The broken lines in the figures illustrate unclaimed environment and form no part of the claimed design.
